UNITED STATES PATENT OFFICE

CHARLES L. FROST AND HORACE E. FROST, OF GRAND RAPIDS, MICHIGAN

LATCH OR LOCK BOLT

Application filed January 14, 1931. Serial No. 508,628.

This invention relates to latch or lock bolts and a simple and very economical yet practical means for actuating the same.

The construction which we have devised is available for the so-called screen door latch and likewise may be used for a door bolt such as a night bolt on doors which have actuating means mounted at the inner side of the door which can be operated only from the inside of the door. It is a primary object and purpose of the present invention to provide a very economical and practical construction useful both with locks and latches and which is efficient and durable in service.

An understanding of the invention may be had from the following description, taken in connection with the accompanying drawing, in which,

Fig. 1 is a fragmentary horizontal section through a door equipped with our invention.

Fig. 2 is a side elevation of the latch or lock bolt and its containing housing.

Fig. 3 is a transverse vertical section through the bolt and its housing substantially on the plane of line 3—3 of Fig. 1, and

Figs. 4 and 5 are elevations of the inner sides of two different forms of operating means for the bolt.

Like reference characters refer to like parts in the different figures of the drawing.

In the construction, a cylindrical housing 1 open at one end and closed at the other and preferably of sheet metal is used which, at its open end, carries a face plate 2 of flat metal to lie against or be inset into the edge of the door in which the structure is installed. This cylindrical housing member has an opening 3 cut in one side as shown in Fig. 1.

Within the housing the bolt proper 4 is slidably mounted and when the bolt is to be used as a latch bolt it has a beveled end 5, but when it is used as a locking bolt the beveled end is not provided but the bolt is

of substantially the same cross section throughout its entire length. The bolt is guided in the housing and held from rotary movement through the provision of a longitudinal slot 6 in the bolt into which an indentation 7 from the housing is made, thereby preventing a rotary movement of the bolt but permitting its free sliding movement. Adjacent its inner end and preferably at a side opposite where the groove 6 is made, a transverse vertical slot 8 is made, being readily cut in the side of the bolt, for a purpose which will hereafter appear. Normally the bolt is projected outwardly by a coiled compression spring 9 within the housing 1 seating against its closed end and bearing against the inner end of the bolt 4 as best shown in Fig. 1.

This bolt with its housing and the spring described within the housing are installed in a door 10 by boring a cylindrical hole inwardly at the free vertical edge of the door until the face plate 2 comes against the edge of the door where it may be fastened thereto by screws in the usual manner. The door has an opening 11 made from one side thereof inwardly toward the housing to join with the opening 3 in the housing.

The manually operated means for operating the bolt is connected to the door over the opening 11 therein. In one form, that shown in Figs. 1 and 4, an escutcheon plate 12 may be secured to the door by screws or other fastenings. At its inner side and housed between it and the door is a lever 13 pivotally mounted at 14 between its ends on the plate and carrying a horizontal pin 15 at its upper end which passes through the openings 11 and 3 and into the slot 8 in the bolt 4. An irregularly shaped operating member 16 for the lever has two spaced apart upwardly extending curved arms 17 and 18, the former of which is longer than the latter and the upper end of which engages against one side of the lever 13 above the pivot 14, while the upper end of the shorter arm 18 engages against

the opposite side of the lever 13 below its pivot. The member 16 is secured to a pivot pin 19 passing through the housing plate 12 and rotatably mounted therein to which, at 5 its outer end, an operating knob 20 is rigidly secured, whereby on rotating the knob in either direction, the lever 13 is swung from its full line position, shown in Fig. 4, to the dotted line position, thereupon moving the 10 pin 15 longitudinally of the housing 1 and withdrawing the latch bolt 4 with a compression of the spring 9; and as soon as the knob 20 is released the spring 9 will return the latch bolt to its normal outer position.

15 In the form of operating means shown in Fig. 5, the escutcheon plate 12a is of a smaller size and the pin 15 which enters the slot 8 of the bolt is carried by an arm 21 of flat metal directly connected to the pivot 19. 20 With this form of operating means the bolt can be retracted only on turning the knob 20 in one direction. Such form of operating means is very useful but for some purposes not quite so desirable as the form shown in 25 Fig. 4 in which the bolt is actuated irrespective of the direction of turning movement of the knob 20.

The construction described is one of a very simple, yet durable and practical nature. 30 The parts are economical to make. The bolt may be machined readily to produce both the groove 6 and the slot 8 and all of the other parts are of a simple nature and can, if desired, be made readily from sheet metal. 35 The invention is defined in the appended claims and is to be considered comprehensive of all forms of structure coming within their scope.

We claim:

40 1. In a construction of the class described, an elongated housing having an opening through one side, a bolt slidably mounted in the housing having a transverse slot at its inner end portion located in conjunction with 45 said opening in the housing, spring means tending to project the bolt outwardly, and an operating mechanism for the bolt comprising, a plate, a member pivotally mounted between its ends at the inner side of the 50 plate, a pin projecting from one end of the member adapted to pass through said opening in the housing and into the slot in the bolt, a knob rotatably mounted on, and at the outer side of said plate, and an actuating device at the inner side of said plate connected to and movable with the knob having two spaced apart upwardly extending fingers, one engaging against the member at one side thereof and at one side of the pivot, 55 and the other engaging with said member at the opposite side thereof and at the opposite side of the pivot.

60 2. In a lock or latch construction having a reciprocable bolt and spring means to press 65 the bolt in one direction the combination of,

a straight arm pivotally mounted between its ends, means at one end of the arm engaging the bolt and a single movable means engaging with opposite sides of the arm upon opposite sides of the pivot whereby the arm 70 will be moved in the same direction regardless of the direction of movement of said single movable means.

In testimony whereof we affix our signatures.

CHARLES L. FROST.
HORACE E. FROST.
